DISPENSING CONTAINER

Roger H. Casler, Oakville, Conn., assignor, by mesne assignments, of one-half to Ex-Cell-O Corporation, Detroit, Mich., a corporation of Michigan, and one-half to a group comprising Ace C. Fessenden, Chicago, Ill., and Ace Carton Corporation, Chicago, Ill., a corporation of Illinois

Application September 27, 1946, Serial No. 699,750

16 Claims. (Cl. 229—17)

1 This invention relates to containers made of paperboard or other sheet material, and more particularly to a liquid-tight and sift-proof container provided with a novel dispensing opening and protective cover flap therefor.

One of the objects of the present invention is to provide in a paper container of the type having a substantially flat top formed by end flaps which are adhesively secured together, a novel dispensing construction which while normally sealed, in order to effectively preserve the contents in a fresh and uncontaminated condition, may be readily and quickly operated in order that the contents may be dispensed in a highly convenient manner.

Another object of the invention resides in the provision of a container dispensing construction of the type which includes a novel arrangement of dispensing opening and overlying protective cover flap therefor, which are respectively formed in a pair of the end flaps of the container blank, and which automatically assume an aligned arrangement as the blank is formed into the container.

A further object includes a novel cover flap construction which, after a portion of the contents of the container have been dispensed, and it is desired to preserve the remainder, may be frictionally engaged with a portion of the container top in order to effectively maintain the cover flap in a closed position.

Still another object resides in constructing the container top and protective cover flap for the dispensing opening in such manner that after the flap is opened, it may be bent rearwardly and frictionally locked with a portion of the container top, this arrangement being especially desirable when it is desired to drink the contents of the container, such as milk for example, directly from the container.

Still another object is to provide a novel container blank construction having side wall panels together with top and bottom flaps so arranged that successive blanks may be formed from a continuously moving web of sheet material without any paper waste.

A further object is to provide a container blank adapted to be folded in such a manner as to provide flange portions at the top of the container connected by continuous webs of the container material together with a pair of end closing flaps respectively provided with a dispensing opening and a cover flap therefor, the end closing flaps being integral with certain of said flange portions and adapted to be bonded to the latter under the

2 application of pressure to secure a positive flow of adhesive between the flaps and flange portions to seal all openings therebetween.

A still further object is to provide a novel dispensing container of the foregoing character which may be manufactured at relatively low cost and which may be quickly set up, assembled and filled with a minimum of number of operations.

10 Other objects and novel features of the invention will appear more fully hereinafter, from the following detailed description when considered in connection with the accompanying drawings, wherein several embodiments of the invention are illustrated. It is to be expressly understood, however, that the drawings are utilized for purposes of illustration only, and are not to be taken as a definition of the limits of the invention, reference being had for this purpose to the appended claims.

In the drawings, wherein similar reference characters refer to similar parts throughout the several views;

25 Fig. 1 is a plan view of a series of container blanks as they are formed from a web of sheet material.

Fig. 2 is a perspective view of a partially assembled container and mechanism for forming the container top;

30 Figs. 3, 4 and 5 are perspective views similar to Fig. 2 and illustrating successive steps in forming the container top;

Fig. 6 is a perspective view of the completed container;

35 Fig. 7 is a partial perspective view of the top illustrating the movement of the cover flap to open position;

Fig. 8 is a view similar to Fig. 7 but showing the cover flap closed and frictionally locked with the webs of the container top;

Fig. 9 is a partial plan view of a modified form of container blank;

Fig. 10 is a partial plan view of still another modified form of container blank;

45 Fig. 11 is a perspective view of a container formed from the blanks of Fig. 9 or 10;

Fig. 12 is a partial perspective view of the top of a container formed from the blank of Fig. 10, and

50 Fig. 13 is a partial perspective view of the container of Fig. 12 after the cover flap is closed.

The present invention is directed to a novel dispensing construction for a container formed of paperboard or similar sheet material, and is particularly adapted to a leak-proof and sift-proof

container of the type disclosed in the copending application of Wilfred A. Eaton, Serial No. 671,832, filed August 23, 1946, for Containers, such application being owned by the same assignee as the present application. In the following description and accompanying drawings, the present invention is described and illustrated as being associated with a container of the type disclosed in the prior Eaton application, but it will be understood that the invention is not limited in its application to containers of this type but may be embodied in containers of various characters.

Referring more particularly to Fig. 1, there is illustrated therein, a plurality of similar container blanks 14, 14a, and 14b adapted to be formed and cut from a web of paperboard or similar sheet material. It will be understood that the blanks may be cut and scored by hand, if desired, but it is preferred that the blank formation take place in a continuous manner by suitable machines.

As shown, each of the container blanks is divided into rectangular wall panels 16, 18, 20 and 22 as by means of scored folding lines 24, the panel 16 being provided with the usual glue flap 26 which is adapted to be adhesively secured to the panel 22. The wall panels 16 and 20 are provided at one end with integral half-flaps 28 and 30, while the panels 18 and 22 are provided with integral full-flaps 32 and 34, the flaps 28, 30 and 32, 34 being thus arranged as to be in opposed relationship when the container is assembled. At the opposite end, the container blank 14, for example is provided with top closing flaps 36 and 38 which are respectively formed integrally with the rectangular panels 18 and 22.

In order to secure the desirable dispensing features heretofore referred to, the present invention provides a novel construction associated with the top flaps 36 and 38, and desirably, such construction is so constituted that successive complete container blanks are cut from the paperboard supply web without wasting any paper. More particularly, and referring to Fig. 1, it is seen that the blanks 14 and 14a are separated by the heavy cut line 39 which defines top flaps 36 and 38 of the blank 14 and corresponding top flaps 36a and 38a of the blank 14a. The division between the aforesaid two blanks is also such that flaps 36 and 36a are respectively provided with dispensing openings 40 and 42 while the flaps 38 and 38a are respectively formed with cover flaps 44 and 46 which are adapted to overlie the respective openings 40 and 42 when the container tops are assembled in a manner to be referred to hereinafter. Preferably, the cover flaps 44 and 46 are provided with tongues 45 and 47 respectively and are connected with their associated top flaps 38 and 38a by score lines 35, forming a hinge and by perforations 37, the latter constituting a weakened joint for enabling tearing the flap to dispensing position, as shown in Fig. 7.

It is particularly stressed that the end of the cover flap 44 of blank 14 is cut out of the flap 36a of the adjacent blank 14a to form the opening 42 in this latter flap. Also, it is observed that the end of the cover flap 46 of blank 14a is cut out of the flap 36 of the adjacent blank 14 and forms the opening 40 in this last mentioned flap. Thus in providing the novel dispensing features of the present invention, including the dispensing openings 40, 42 and the cover flaps 44 and 46, the adjacent blanks 14 and 14a are complementary and no material is wasted.

Blanks 14a and 14b are, as shown, separated by

the heavy cut line 48 which is so arranged as to separate these blanks along lines which insure a disposition of full and half flaps on these respective blanks, similar to the flaps 28, 30, 32 and 34 of the blank 14. Thus blank 14a is formed with integral full flaps 32a, 34a and integral half flaps 28a and 30a while the blank 14b is provided with full flaps 32b, 34b and half flaps 28b and 30b. In this manner the web of paperboard material is transversely cut at proper intervals along its length to provide alternate cut lines similar to the lines 39 and 48, and the successive blanks may be readily separated by removing the ends of the cover flaps 44 and 46 from the respective openings 42 and 48.

During formation of the blanks, in addition to the score lines heretofore mentioned, certain others are impressed on each blank in order that opposite ends of the blank may be folded in such manner as to secure a leak-proof top and bottom for the container. More particularly the half flaps 28 and 30 of the blank 14 are provided with respective score lines 50 and 52 for facilitating the formation of a leak-proof container bottom. With respect to the other end of the blank, a score line 54 defines, in cooperation with angularly disposed score lines 56, 58, 60 and 62, substantially isosceles trapezoidal shaped panels 64 and 66 at the right ends of wall panels 16 and 20, and adjacent substantially triangular panels 68, 70, 72 and 74. Additional score lines 76 and 78 define, in conjunction with the score line 54 and the horizontal score lines 24 rectangular panels 80 and 82 at the right ends of panels 18 and 22 respectively. Other angularly disposed score lines 84, 86, and 88, 90 on panels 16 and 20 respectively, together with score lines 24 and 54, define a pair of triangular panels 92 and 94 on wall panel 16 and a pair of triangular panels 96 and 98 at the right end of wall panel 20. If desired, an additional vertically arranged score line 100 may be provided, which defines, in conjunction with score lines 84, 54, 86, 88 and 90, isosceles trapezoidal shaped panels 102 and 104 at the right ends of wall panels 16 and 20 respectively. It is observed that rectangular panels 106 and 108 are formed on the respective panels 18 and 20 by the score lines 24, 54 and 100.

In assembling the bottom flaps 28, 30, 32 and 34 to form the container bottom, all of the aforesaid flaps are provided with flowable adhesive coatings 110, as shown, and the flaps are preferably assembled in the manner disclosed in the copending application of Roy S. Sanford and Wilfred A. Eaton, Serial No. 644,547, filed January 31, 1946, for Paper Container, owned by the same assignee as the present application. More particularly, and as set forth in the Sanford and Eaton application, after the blank 14 has been formed into a tube, by joining the glue flap 26 to the wall panel 22, the bottom closure is formed by folding the half flaps 28 and 30 about the score lines 50 and 54 respectively to bring the adhesively coated surfaces together. Thereafter, the half flaps of double thickness are folded inwardly to a position at right angles to the container walls, following which the flaps 34 and 32 are folded inwardly in the order named. Thereafter, the flaps, thus assembled are subjected to pressure to effect a firm bond therebetween and to positively flow the adhesive coatings thereon into all cracks and pin holes between the flaps and between the flaps and container walls, thus forming a leak-proof substantially flat closure for the bottom of

75 the container.

Assuming that the bottom of the container has been formed and sealed as above described, and that the container has been waxed or otherwise coated with a suitable moisture proof material, should such coating be desirable in view of the nature of the contents, it is only necessary to fill the container with the desired material following which the top may be closed and sealed in accordance with the method described in the aforementioned Eaton application. More particularly, the container is placed on a forming and sealing machine 112, Fig. 2, being supported at its lower end by a suitable support, not shown. The container now has a rectangular cross section and the upper end is open, with the end closing flaps 36 and 38 extending upwardly from panels 80 and 82. The machine is provided with a pair of opposed relatively movable members such as slides 114 and 116, the width of member 114 at its inner end being the same as or slightly less than the length of the upper side of panel 102, and the width of the inner end of member 116 being the same as or slightly less than the length of the upper side of panel 104. Another pair of opposed movable members such as slides 118 and 120 are mounted in the machine for movement substantially at right angles to the direction of movement of members 114 and 116, the widths of members 118 and 120 being substantially the same as the widths of wall panels 18 and 22 respectively. As shown, the movable members are guided for rectilinear movement by guides 122, suitably secured to the machine. A rectangular plunger 124 is mounted for vertical movement on a portion of the machine in any suitable manner, not shown, the plunger being of substantially the same shape and size as the cross section of the container, and preferably having the four corners of the bottom surface relieved slightly at 126, thus providing centrally positioned portions 128 on each side of the plunger.

In order to form the upper part of the container preparatory to sealing the latter, the plunger 124 is initially moved downwardly within the open end of the container to a position where its lower surface is slightly above the level of the upper surfaces of the movable slides. The latter, whose upper surfaces are slightly below the score line 54 on the container are substantially simultaneously moved inwardly until they assume the positions shown in Fig. 3. During such inward movement of the slides 114, 116, 118 and 120, the panels 102, 104, 106 and 108, respectively engaged thereby, are folded inwardly about the score line 100. At the same time, panels 64, 66, 80 and 82 are engaged by the portions 128 of the plunger 124 and are folded outwardly to form a substantially horizontally positioned flat flange around the upper end of the container, the substantially triangular panels 68, 70, forming connecting webs between the flange forming panel 64 and flange forming panels 82 and 80, and the substantially triangular panels 72 and 74 forming continuous webs between flange forming panels 80 and 82. The flange forming panels and the substantially triangular panels are all folded outwardly with respect to their original positions, see Fig. 3, and flange supporting panels 102, 104, 106 and 108 and the adjacent triangular panels 92, 94, 96 and 98 are all folded inwardly, the latter panels serving to form webs between the flange supporting panels and to form four strengthening ribs adjacent the top of the container, see ribs 130 and 132 of Fig. 7.

Following the above procedure, the plunger 124 is retracted as shown in Fig. 4, and after folding the flaps 36 and 38 inwardly as shown in Fig. 5, a second plunger or pressure plate 134, preferably having a flat lower surface of slightly larger area than the flap 38 is moved downwardly to engage the upper surface of flap 38 and to press the top flaps 38 and 36 and the flange forming panels 64, 66, 80, and 82 together to effect a firm bond therebetween and to positively flow the adhesive coatings 110 to seal all openings and pin holes, the flange forming panels being effectively supported during this operation by the slides 114, 116, 118 and 120 in order to permit the application of any desired force by operation of the pressure plate 134. As soon as a bond has been effected and the adhesive flowed into the openings between the flange forming panels and between the latter and the end closing flaps to seal all cracks and openings, the pressure plate 134 and the slides 114, 116, 118 and 120 may be retracted to permit removal of the filled and sealed container from the forming machine.

During the above described top sealing operation, it will be understood that the tongue 45 of the cover flap 44 is moved downwardly in any suitable manner so as to lie against the outside surface of the flange forming panel 66. Thereafter, the slide 116 during its movement toward the container engages the tongue 45 following which the steps of sealing the top flaps set forth heretofore, are performed. When the latter operations have been completed, it will be noted from Figs. 6, 7 and 8, that the tongue 45 is tucked beneath the flange forming panel 66, this action being facilitated by providing the tongue with spaced-apart score lines 136 and 138.

In order to provide a top closure possessing a high degree of strength and rigidity, it is contemplated that the slides 114, 116, 118 and 120 may be moved inwardly a sufficient distance to substantially effect engagement of the inner surfaces of panels 94 and 96 with panel 106 on the one hand, and of panels 92 and 98 with the panel 108 on glue flap 26 on the other. In this manner, see Fig. 7, the ribs 130 and 132 are formed which serve to materially stiffen and rigidly support the flange forming portions at the top of the container, and also provide opposed recesses 140 which permit the user to readily grasp and lift the container. It will be noted that during the top sealing operation, the adhesively coated surfaces of the substantially triangular panels 68, 70, 72 and 74 engage the adhesively coated surfaces of the adjacent rectangular flange forming panels 80 and 82 and are firmly bonded thereto to form a strong reinforcement at the corners of the top closure.

One of the features of a container top constructed as above described resides in so constructing the blank that when assembled into a container, the dimension A of Fig. 7 will be less than the dimension B. Such an arrangement provides clearance between the top edges of the containers when packed in a carton to enable the user to readily grasp and remove the containers therefrom. To this end, the score lines 56, 58, 60 and 62, which are preferably arranged at an angle of 45°, as set forth in the prior Eaton application, are so positioned that the distance between the upper ends of the score lines 56 and 58 is less than the width of the wall panel 16 while the distance between the upper ends of the score lines 60 and 62 is less than the width of the wall panel 22. Thus when the panels are folded and

the top assembled and sealed in the manner heretofore described, the dimension A, which is substantially the same as the aforesaid distances between the upper ends of the score lines, is less than dimension B, the latter corresponding of course, to the width of the wall panels 16 and 22.

After the container has been formed, filled and sealed in the manner set forth above, the contents thereof may be readily dispensed by merely lifting the tongue 45 to tear the cover flap 44 along the weakened lines 37 and expose the opening 40, it being understood that during this operation, the cover flap 44 remains hinged to the top flap 38 by the score line 35. It will be noted that the opening 40 is so shaped that the pouring edge 142 thereof terminates short of the score line 54 which forms the juncture between the panel 104 and the flange forming panel 66. This construction thus assures a sharp lip at the edge 142 which eliminates any tendency toward dripping of the contents.

A highly important feature of the invention resides in the provision of an arrangement for locking the cover flap in closed position after a portion of the contents have been dispensed and it is desired to keep the remainder for future use. In the form of the invention shown in Figs. 1-8 inclusive, such desirable arrangement is achieved by making the dimension C of the cover flap 44 slightly wider than the distance between the upper ends of the ribs 130 and 132, shown as dimension D in Fig. 8. With such a construction it will be readily understood that when it is desired to close and lock the flap 44, it is only necessary to move the same from the position shown in Fig. 7 to that shown in Fig. 8 whereupon the outer edges of the portion 144 of the flap 44 between the score lines 136 and 138 will become frictionally engaged with the upper and adjacent portions of the ribs 130 and 132. It will also be appreciated that due to this construction, the flap 44 is frictionally locked in closed position during the assembly of the top, thus materially facilitating this operation.

In the form of the invention heretofore described it will be recalled that the blanks are cut from a continuous web of paperboard without waste of material. This is achieved by forming the dispensing or pouring opening of one blank by cutting from one of the top flaps thereof, a portion of the cover flap of an adjacent blank. While this construction saves material, it will be noted that the pouring opening 40 of the flap 36 for example is completely open at one edge, see Figs. 2-5. With this arrangement, when the top flaps are assembled, the top flaps 38 will be bonded directly to the flange forming panel 64 over a major portion of the length of the latter, without having a continuous portion of the top flap 36 therebetween, as occurs at the opposite edge of the flap 38 when it is assembled with respect to the flange forming panel 66. Thus the strength at one edge of the completed top may not be as strong as that at the opposite edge.

In Fig. 9 there is disclosed a modified form of blank 146 which is so arranged that the corresponding opposite edges of the container top are of equal strength. As shown, the blank 148 is similar to blank 14 except that each blank is separately stamped or cut from the web material and the flap 36 is continuous around the opening 40 rather than being cut away to leave open one edge of the dispensing opening 40 as in the case of the first form of the invention. Thus in the modified form, when the top is assembled and

sealed, a portion of the top flap 36 will be interposed between the flange forming panels 64, 66 and the top flap 38 to provide opposite edges of equal strength.

It will also be noted in connection with Fig. 9 that the weakened line 150 joining the cover flap 44 to the top flap 38 is constituted by zig-zag perforations rather than by straight perforations as in Fig. 1, it having been found in practice, that the use of a zig-zag tear line materially improves the strength of the container top.

Since the container of the present invention may be advantageously employed for the packaging of milk, Figs. 10-13 illustrate a further form which is similar to that shown in Fig. 9 except that it is so constituted as to greatly facilitate the drinking of the contents directly from the container. For this purpose, the cooperating edges 152 and 154 of the top flap 36 and the flange forming panel 66 respectively, are curved, see Fig. 10, so that when the top is assembled and bonded, in the manner heretofore described in connection with Figs. 1-8, and the cover flap 44 is torn to the position shown in Fig. 12, a curved edge 156 will be presented to the lower lip of the user. While the opening 40 may take any desirable configuration it is preferred that the edge over which the contents are dispensed be curved as shown at 158 in Fig. 10. With this arrangement of curved edges 156 and 158, the user may drink directly from the container without danger of spilling any of the contents.

A further feature of the form shown in Fig. 10 resides in constructing the cover flap 44 in such manner that it may not only be frictionally locked in closed position after initial opening, as in the two forms previously described, but may also be frictionally locked in open position to further facilitate drinking directly from the container. To this end, the score line 35, forming the hinged connection between the cover flap 44 and the top flap 38 is arranged substantially midway between opposite edges of the latter. Thus after the flap 44 has been opened, it may be moved upwardly and rearwardly into engagement with the top surface of the flap 38, and the panel 144 tucked into the recess 140 at the rear of the container, as viewed in Fig. 13. Frictional engagement between the opposite edges of the panel 144 and the upper and adjacent sides of the ribs 130 and 132 at the rear of the container will thereupon lock the cover flap 44 in open position, precisely in the same manner, as the cover flap may be locked in closed position after being initially opened.

Preferably, the bottoms of the blanks of Figs. 9 and 10 are constituted in the same manner as the blank of Fig. 1 and the tops of the modifications are folded, assembled and bonded as in the first form of the invention. However, it will be understood that the opening features of the invention may be utilized with containers wherein the bottoms and tops are formed otherwise than as disclosed in Figs. 1-8, if desired.

It has been previously stated, in connection with the formation of the top of the container, that the latter may be coated with wax or other suitable material prior to filling and thereafter closing and sealing the top. Such a sequence of operations is merely illustrative and by way of example only. A further desirable sequence might be the closing and bonding of the flap 36 to the flange forming panels 64, 66, 80 and 82; the subsequent waxing or coating of the interior and exterior surfaces, the coating material being applied 75 and removed from the interior through the dis-

pensing opening 40, and the final filling of the container through opening 40 and the closing and sealing of the top flap 38. It will be understood that if desired, the steps of filling the container and the final permanent sealing of the flap 38 may be performed where the filling operation is to take place, at a dairy for example. In such event, the containers may be shipped in a set-up waxed condition with the flap 38 permanently bonded to the flange forming panels 64, 66, 80 and 82, and the top flap 38 temporarily sealed by the application of a slight amount of heat just sufficient to melt the wax coating on the underside of the top flap 38. This would enable the flap 38 to be opened for filling the container through the opening 40, whereupon the flap 38 may be permanently bonded to the top by the application of pressure in the manner heretofore described, it being understood that the flap 44 is moved against the panel 104 so that the opposite edges thereof are frictionally engaged with the ribs 130 and 132.

From the foregoing, it will be readily perceived that the present invention provides a novel blank and container structure which may be readily formed in a single piece from paperboard or other similar sheet material. The arrangement of the blanks in Fig. 1 is such that no material is wasted, notwithstanding each blank is provided with a top dispensing opening and a protective cover flap of generous size. Of particular importance is the construction of the cover flap 44 and its cooperation with the container top whereby the flap may be locked in either open or closed position. Further features reside in the provision of a non-drip dispensing opening together with the curving of the edges 156 and 158 which materially facilitates drinking directly from the container without spilling. It will also be noted, that in all forms of the invention the contents of the container are poured over a surface of one of the top flaps which is normally completely covered and protected by the cover flap, thereby resulting in a highly sanitary construction.

It will be understood that in assembling the tops of any of the containers heretofore described, it is not necessary to bond the tongue 45 of the cover flap 44 to the exterior of the panel 104. In practice, the tongue is preferably forced against said panel by any suitable heated element whereupon the melted wax or other coating, when cooled, causes the tongue to effectively adhere to the outer surface of the panel 104. To lift the flap 44, it is only necessary for the user to insert his fingernail or the point of a knife under the lower edge of the tongue, then grasp the latter and pull upwardly to expose the dispensing opening 40, see Figs. 7 and 12.

While several forms of the invention have been shown and described herein, with considerable particularity, it will be understood by those skilled in the art, that various modifications may be resorted to without departing from the spirit of the invention. For example, while the novel dispensing opening and protective cover flap construction has been shown in connection with a container top formed in a particular manner, it will be perceived that such construction may be employed with container tops of various types. Reference will therefore be had to the appended claims for a definition of the limits of the invention.

What is claimed is:

1. A tubular paperboard container having a bottom and side walls, outwardly extending flanges formed at the upper ends of said side walls, an end flap adhesively secured to said flanges and

provided with a dispensing opening, and a second flap overlying the first flap and adhesively secured thereto, said second flap being weakened along lines defining a tear strip overlying said opening, and said tear strip having a tongue folded around one of said flanges to substantially cover the exposed portions thereof of adjacent said opening.

2. A tubular paperboard container having a bottom and side walls, outwardly extending flanges formed at the upper ends of said side walls, an end flap integral with one of said side walls, adhesively secured to said flanges and provided with a dispensing opening, and a second flap, integral with another of said side walls, overlying the first flap and adhesively secured thereto, said second flap being weakened along lines defining a tear strip overlying said opening, and said tear strip having a tongue folded around one of said flanges to substantially cover the exposed portions thereof of adjacent said opening.

3. A tubular paperboard container having a bottom, side walls and a flat top, said top being provided with a dispensing opening and a protective, overlying cover flap therefore, said flap being connected to the top by a pair of weakened lines, one of said side walls being formed to provide a pair of spaced apart strengthening ribs below the top, and a lifting tongue connected with said cover flap and having its opposite edges frictionally engaged with said ribs.

4. A tubular paperboard container having a bottom, top and side wall construction, said top having a dispensing opening with an overlying protective cover flap therefor, said flap being hinged to the top along one edge and being also connected with the top along other edges by weakened lines so that the flap may be partially torn from the top and moved about the hinged connection to expose the dispensing opening, the flap being of such length as to provide a tongue bent over the edge of the top and lying against the container side wall, and means formed on the side wall for frictionally engaging opposite edges of said tongue to releasably lock the flap in closed position to cover the opening, after the flap has been initially opened.

5. A tubular paperboard container as set forth in claim 4 wherein the top is provided with an outwardly directed peripheral flange and the tongue is bent over the edge of the flange and under the latter.

6. A tubular paperboard container having a bottom, top and side wall construction, said top having an outwardly directed peripheral flange and having also, a dispensing opening with an overlying protective cover flap therefor, said flap being hinged to the top along one edge and being also connected with the top along other edges by weakened lines so that the flap may be partially torn from the top and moved about the hinged connection to expose the dispensing opening, the flap being of such length as to provide a tongue bent over and beneath the flanged edge of the top and lying against the container side wall, and means including a pair of spaced apart strengthening ribs formed on the side wall for frictionally engaging opposite edges of said tongue to releasably lock the flap in closed position to cover the opening, after the flap has been initially opened.

7. A tubular paperboard container having a bottom, side walls and a top, the latter being provided with a dispensing opening and a pouring surface extending outwardly from one of the container side walls and over which the container

11

contents may be poured, a protective cover flap hingedly connected with the top and overlying said opening and pouring surface, said flap being also connected to the top along weakened lines allowing the flap to be partially torn from the top and moved about said hinged connection to expose said opening and pouring surface, and spaced apart ribs formed on said one side wall of the container to frictionally engage opposite edges of a portion of said flap to releasably lock the flap in closed position.

8. A tubular paperboard container having a bottom, side walls and a top, the latter being provided with a dispensing opening and a pouring surface extending outwardly from one of the container side walls and over which the container contents may be poured, a protective cover flap hingedly connected with the top and overlying said opening and pouring surface, said flap having a tongue lying against said one side wall and being bent beneath said pouring surface, and spaced apart strengthening ribs formed on said one side wall to frictionally engage opposite edges of said tongue to releasably lock the flap in closed position.

9. In a container of the type having a bottom and side walls, a top dispensing closure therefor comprising outwardly folded flange forming panels at the upper end of each side wall, outwardly folded strengthening ribs formed on said side walls and connecting said panels, an end side wall and connecting said panels, an end closing flap, means for adhesively securing said flap to said flange forming panels said flap having a portion associated therewith along weakened lines to allow said portion to be partially torn from the flap to open said container, and a tongue extending from said portion over and beneath one of said panels and having each of its opposite edges frictionally engaged with one of said ribs to releasably lock the flap in closed position.

10. In a container of the type having a bottom and side walls defining a substantially rectangular cross section, a top dispensing closure therefor comprising outwardly folded flange forming panels at the upper end of each side wall, outwardly folded strengthening ribs formed at the adjacent edges of said side walls at the top thereof and connecting said panels, an end closing flap integral with one of said side walls, means for adhesively securing said flap to said flange forming panels, said flap having a dispensing opening therein, a second end closing flap integral with another of said side walls and adhesively secured to said first flap, the second flap having a portion associated therewith along weakened lines to allow said portion to be partially torn from the second flap to expose said opening and a tongue extending from said portion over and beneath one of said panels and having each of its opposite edges frictionally engaged with one of said ribs to releasably lock the flap in closed position.

11. A paper container comprising a body of substantially rectangular cross section and a flat end closure therefor, said body being provided adjacent its upper end with a plurality of inwardly directed panels connected with a plurality of outwardly directed panels forming a marginal flange at the upper end of the body, said inwardly directed panels forming strengthening ribs at the juncture between each panel and adjacent panels, an end flap adhesively secured to said marginal flange and provided with a dispensing opening, and a second flap overlying the first flap

5 and adhesively secured thereto, said second flap being weakened along lines defining a tear strip overlying said opening and a portion of said flange, and said tear strip having a tongue folded beneath said portion of the flange and having opposite edges respectively frictionally engaged with adjacent ribs to releasably lock the strip in closed position.

12. A plurality of adjacent container blanks formed to match at opposite ends thereof, the matching ends of a pair of adjacent blanks being defined by an irregular continuous cut line to provide alternate matching end flaps, an end flap of one blank having an integral tear strip provided with a tongue cut out of an adjacent end flap of the other blank to form a dispensing opening in the latter flap, and an end flap of said other blank having a similar integral tear strip provided with a similar tongue cut out of an adjacent end flap of said one blank to form a dispensing opening in the last mentioned flap.

13. A tubular paperboard container having a bottom, side walls and a top, the latter being provided with a dispensing opening and a pouring surface extending outwardly from one of the container side walls and over which the container contents may be poured, a protective cover flap hingedly connected substantially centrally of the top and overlying said opening and pouring surface, a pair of ribs formed on said one side wall of the container adjacent said pouring surface and spaced apart a slightly lesser distance than the width of said flap to frictionally engage opposite edges of a portion of said flap to releasably lock the flap in closed position to cover the opening, and a second pair of ribs formed on the side wall opposite said one side wall and also spaced apart a slightly lesser distance than the width of said flap to frictionally engage opposite edges of a portion of said flap to releasably lock the flap in fully open position.

14. A flat blank for a tubular container of rectangular cross section, comprising a sheet of paperboard material scored and cut to provide side wall panels, bottom closing flaps at one end of said side wall panels and a plurality of flange panels at the other end of said side wall panels, the flange panels forming outwardly extending marginal flanges when the blank is folded into a container, a pair of top closing flaps respectively formed integrally with a pair of flange panels, one of said top flaps being provided with a centrally positioned dispensing opening and a surface over which the contents of the container, when the container is assembled, may be poured, and the other top flap having a tear strip provided with a lift tab extending beyond the margin of said other top flap, the tear strip, when the container is assembled, overlying said opening and said surface and the lift tab being folded around one of said flanges.

15. A flat blank for a tubular container of rectangular cross section, comprising a sheet of paperboard material scored and cut to provide side wall panels, bottom closing flaps at one end of said side wall panels and a plurality of flange panels at the other end of said side wall panels, adjacent flange panels being connected by substantially triangular foldable panels, the flange panels and the foldable panels forming outwardly extending and continuous marginal flanges when the blank is folded into a container, a pair of rectangular top closing flaps respectively formed integrally with a pair of alternate flange panels, one of said top flaps being pro-

13

vided with a centrally positioned opening and a surface over which the contents of the container, when the container is assembled, may be poured, and the other top flap being weakened along lines defining a tear strip intermediate two side edges of said other flap and hingedly connected thereto, the tear strip having a lift tab extending beyond the margin of said other top flap and toward said one end flap, the tear strip, when the container is assembled, overlying said opening and said surface and the lift tab being folded around one of said flanges.

16. A flat blank for a tubular container of rectangular cross section, comprising a sheet of paperboard material scored and cut to provide side wall panels, bottom closing flaps at one end of said side wall panels and a flange panel at the other end of each of said side wall panels, adjacent flange panels being connected by substantially triangular foldable panels, the flange panels and the foldable panels forming outwardly extending and continuous marginal flanges when the blank is folded into a container, a pair of rectangular top closing flaps respectively formed integrally with a pair of alternate flange panels, one of said top flaps being provided with a centrally positioned opening and a surface over which the contents of the container, when the container is assembled, may be poured, the free edge of said one top flap facing the other top flap being curved inwardly, and the free edge of

14

5 the flange panel positioned between the top flaps being similarly curved inwardly, and the other top flap being weakened along lines defining a tear strip intermediate two side edges of said other flap and hingedly connected thereto, the tear strip having a lift tab extending beyond the margin of said other top flap and toward said one top flap, the tear strip, when the container is assembled, overlying said opening and said surface and the lift tab having a portion thereof foldable around one of said flanges to engage the under portion of said one flange.

ROGER H. CASLER.
